UNITED STATES PATENT OFFICE.

GEORGE VIRNEBURG, OF NEW YORK, N. Y.

SWIMMING GLOVE.

Application filed December 19, 1924. Serial No. 756,860.

The object of this invention is to provide a swimming glove of simple construction and yet one that will be strong and serviceable, but, the most important object of the invention is to provide a glove of universal application, that is a glove that may be employed by anyone, almost regardless of the size of the hand.

Swimming gloves have been known in the past and some have been produced of the shape and size similar to the glove here shown and described, but, these gloves have not found a general use, for the reason that insufficient care has been taken in their construction, with the result that they have not withstood the strenuous duties they are called upon to perform.

Another reason for the failure of these gloves to become generally adapted is that, in the past, it has been found necessary to make them of different sizes, to such an extent that the cost of construction has been increased as well as the cost of marketing.

Another reason for the failure of swimming gloves, in the past and one that has received my special attention, is, that swimmers require that the swimming glove fit snugly around the wrist and that it have the feeling of security, when in use.

Gloves fastened by means of buttons or snaps fail in this most important detail.

Other advantages of my invention and the construction by which all of these advantages are attained will be set forth as the specification progresses and the accompanying drawing should be referred to for a complete understanding of the specification which follows.

In the drawing:—
Fig. 1, is a view in elevation, showing my glove tightly closed.

Fig. 2, is a view, partly in section. This view shows the back of the glove and the fractured portions show the construction.

Fig. 3, is a sectional view of a small part, showing the method of reinforcing.

Fig. 4, is a similar view of the part directly opposite.

Fig. 5, is a view similar to that shown in Fig. 3, but having a different type of fastening.

Fig. 6, is a sectional view of one edge at the wrist. This view is taken on the line 6 of Fig. 2.

Similar reference numerals indicate like parts in all the figures where they appear.

My glove is formed of two main portions of flexible material, preferably a light fabric and the two main portions are of similar shape and size. These two main portions are shown at 1 and 2 in Figs. 1 and 2 and after being connected in a suitable manner are secured together by a row of stitches 3, extending around the entire outline of the glove with the exception of a small portion, which will provide an opening for the insertion of the hand. A second row of stitches 4, which also secures the main parts 1 and 2, serves to divide the glove up into finger recesses.

In the portion 1, which I may refer to as the front member, I provide an elongated slit 5, the glove opening, and which makes it possible to insert the hand into the glove with little difficulty and in the back member 2, I provide a plurality of small slits or openings as shown at 6, 7, 8 and 9, suitably bound with stitching as shown at 10. These openings ventilate the glove and allow the free ingress of water into the glove and the 80 free egress of water from the glove.

Upon the wrist of my glove or upon that portion which will form the wrist, I place a reinforcing band as shown at 10 and this is important as the glove will be made of 85 material, light of weight and thin of texture.

I call attention to the webs 11, 12 and 13 and 14, between the fingers and between the fingers and thumb portion of the glove. Such webs, are, however, common in swim- 90

I call particular attention to the construction of this glove and it will be noted, as shown at 15 in Fig. 2, that the edges of each part are turned in prior to stitching and I 95 further call attention to the construction of the wrist portion of the glove where it will be noted that the material of each part is turned inwardly as shown at 16 and the parts are then secured together, the wrist band 10 being secured to the inwardly turned portion 16 of the glove, thus adding strength.

The construction of my glove can be fully appreciated by referring to Figs. 3 to 6 inclusive, where the reinforcements are definitely shown.

To be successful a swimming glove must be adjustable to a very great extent and readily secured or loosened. For this reason, 110 buttons or clasps are not found desirable, not only because of their lack of adjustment,

but because they cannot be readily engaged or separated.

A glove that lacks adjustment requires that such glove shall be bought to fit. This requires the carrying of numerous sizes by the dealer and also increases the cost of manufacture. As these gloves are, at best, a low priced article, their construction must be so simplified that unnecessary expense shall never be assumed.

With these ideas in mind, I have designed the fastening means shown, which consists of a plurality of buttons 17 and 18, secured to the glove in a suitable manner and under 15 one button I secure the end of a cord 19, which may be wrapped about the buttons as shown in Fig. 1.

The cord 19 may be sufficiently long to allow a very great range of adjustment and 20 any type of button may be used, such as the post secured button 20, shown in Fig. 5.

Modifications may be made within the scope of the appended claim without de-

parting from the principle or sacrificing the advantages of the invention.

Having carefully and fully described my invention, what I claim and desire to obtain is:—

A swimming glove formed of two pieces of flexible material of equal size and similar outline, said pieces being secured together and a reinforced wrist band formed by having the material of each part folded upwardly and inwardly, prior to the joining of the parts together and securing an additional flexible member exterior of said parts and around said wrist portion, said glove having a button arranged adjacent to each end of said additional flexible reinforcing member and a cord between said buttons for drawing them toward each other in adjustable relation.

Signed at the city, county and State of New York, this 3rd day of December, 1924.

GEORGE VIRNEBURG.
